CLAIM

I claim the ornamental design for a pail adapter, as shown and described.

DESCRIPTION

FIG. 1 is a bottom perspective view of a pail adapter showing my new design;

FIG. 2 is a top perspective view thereof;

FIG. 3 is a bottom view thereof;

FIG. 4 is a top view thereof;

FIG. 5 is a right side elevation view thereof, the left side view being the same;

FIG. 6 is a front elevational view thereof, the rear view being the same;

FIG. 7 is a cross-sectional view taken along line 7-7 in FIG. 4; and,

FIG. 8 is a cross-sectional view taken along line 8-8 in FIG. 3.

The cross-sectional views shown in FIGS. 7 and 8 are provided to clearly bring out the elements of the claimed design.

The parallel lines are surface shading used to indicate the character and contour of the various surfaces of the claimed design.
